Primary Examiner — Mimosa De(74) Attorney, Agent, or Firm — Heslin Rothenberg Farley & Mesiti P.C.(57) CLAIM

The ornamental design for a chaise lounge, as shown and described.

DESCRIPTION

FIG. 1 is a perspective view of a chaise lounge in accordance with the new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top view thereof; and,

FIG. 7 is another perspective view of the chaise lounge with the back lowered.

The broken lines in the figures are for illustration purposes only and form no part of the claimed invention.
